UNITED STATES PATENT OFFICE.

ANGELO DE STEFANO, OF RIDGEFIELD PARK, NEW JERSEY.

MUSIC-LEAF TURNER.

1,363,063.

Specification of Letters Patent. Patented Dec. 21, 1920.

Application filed March 8, 1918. Serial No. 221,239.

To all whom it may concern:

Be it known that I, ANGELO DE STEFANO, a citizen of the United States of America, residing at Ridgefield Park, in the county 5 of Bergen and State of New Jersey, have invented new and useful Improvements in Music-Leaf Turners, of which the following is a specification.

This invention relates to improvements in 10 music leaf turners and seeks for its principal object to simplify and reduce the expense of manufacture of devices of this character, the same employing a minimum number of parts, which effectively operate at all times 15 to accomplish a purpose for which they are designed.

Another object of the invention is the provision of a music leaf turner which is so constructed as to allow the arms which carry 20 the sheets, to be readily turned in either direction independently of the mechanism for operating the same.

Another object of the invention is the provision of a music leaf turner comprising a 25 plurality of swinging arms arranged in superposed relation, an actuator arranged above said arms, means for transmitting motion to the actuator and a spring pressed trigger vertically movable through said actuator and provided at its lowermost end with means for successively engaging the 30 arms and correlating the same with the actuator for turning the leaves successively.

With these and other objects in view the 35 invention resides in the novel construction, combination and arrangement of parts, fully described and pointed out in the following description and claims and illustrated in the accompanying drawings in which—

40 Figure 1, is a front elevation of the device.

Fig. 2, is a horizontal section on the line 2—2, of Fig. 1, looking in the direction indicated by the arrows.

Fig. 3, is a vertical section on the line 45 3—3, of Fig. 1, looking in the direction indicated by the arrow.

Fig. 4, is a diagrammatic view of the arms and the trigger.

Figs. 5, 6 and 7 are detail views illustrating the manner in which the arms 14 are moved from one side to the other of the device successively.

Referring to the drawings, 10 designates

a base plate which is provided with the pivoted clamp 11, the same being designed as a means for clamping the device to the stand or other article to which the device is to be applied, and which also serves as a means 55 for positioning the book or sheet music thereon. Secured to the plate is a casing 12, which is provided with a pivot pin 13, extending vertically therein, upon which are mounted for swinging movement the arms 60 14, which are provided at their outer ends with any suitable clamping means 15, for engagement with the music leaves. Each arm 14 is provided with an enlargement 14^a the purpose of which will appear hereinafter. 65 Mounted above the arms 14, on the pin 13, is an actuator 16, which is provided with teeth 17, and an outwardly extending arm 18, having a sleeve 19, through which a trigger pin 20, is adapted to slide. The pin is 70 provided at its lower end with an enlarged head 21, having a reduced lug 22, projecting downwardly therefrom and the sleeve is provided with an enlarged bore at its lower extremity forming a shoulder 23, therein between which and the head 21, is inserted a coiled spring 24, whereby the trigger is normally projected toward the arms 14, as is clearly shown in Fig. 3 of the drawings. The lug 22 is adapted to ride over the enlargement 75 14^a of the arms. The lug 22 is of a length equal approximately to the thickness of either of said arms. Therefore it is impossible to move more than one arm at a time. The trigger is provided at its upper 80 end with a manipulating portion 25, and has a stop pin 26 therein, which is adapted to engage the upper extremity of the sleeve whereby the trigger may be locked in an inoperative position when desired. Extending 85 transversely of the casing 12, is a bar 27, provided with rack teeth 28, for engagement with the teeth 17, on the actuator. One extremity of the bar 27, is reduced as at 29, to form a shoulder 30, between which and the 90 side of the casing is interposed a coiled spring 31, the purpose of which is to normally project the bar 27, in one direction. The opposite extremity of the bar is provided with an opening 32, in which is received a flexible shaft 33, which is provided with an operating head 34. This operating means may also be used in connection with 100

a foot pedal and may be positioned at any point within convenient reach of the musician. A stop member 35, is provided adjacent the pin 13, and projects upwardly 5 through the bottom of the casing where it is adapted to be engaged by the arms in either direction to limit the movement thereof. This stop positions the arms with relation to the trigger to cause the same to positively 10 bring the lug 22, into proper place. The lower side and front walls of the casing are slotted as at 36, to provide a working space for the arms and the upper wall of the casing is provided with an arcuate slot 37, 15 which receives and guides the upper extremity of the sleeve 19.

To turn the leaves or sheets of the music to be played individually, the operating head 34 is moved toward the bar 27 and this action through the intervention of the parts 20 17, 18 and 19 cause the pin 20 to move in an arc. Inasmuch as the lug 22, in its normal position, is in engagement with the uppermost arm 14, the same will be caused to move 25 to its other extreme position. Upon removal of pressure on the head 34, the spring 31 will function to cause the return movement of the pin 20 and in the return movement of the pin 20, the lug 22 will ride over the enlargement 14^a of the next uppermost arm 14 until it clears the back edge thereof, when 30 the spring 24 will impart a downward movement to the pin 20 causing the lug 22 to be positioned behind the arm 14. The head 21 35 limits the downward movement of the pin 20. It will be understood that the pin 20 is capable of reciprocatory, arcuate and turning movements.

In Fig. 5 one of the arms 14 is shown 40 about to be moved to an opposite extreme position from over the aligned arms beneath.

Fig. 6 is a sectional view taken on the line 6—6 of Fig. 5. Fig. 6 shows the relative disposition of the parts as shown in Fig. 5.

Fig. 7 shows the lug 22 disposed behind the arm 14^a next lowermost to the arm 14 being moved as in Fig. 5. The lug 22 never rode off of the enlarged part 14^a of the arm 14^a until it arrived at the back edge of the 50 arm 14^a, at which point the said lug is projected down behind the arm 14^a by the spring 24. Such operation is repeated until all of the arms have been moved by the mechanism, when they are returned by hand to 55 their other extreme positions.

While I have shown and described a simple and preferred form of the invention, I do not care to be limited to the exact details therein exhibited but desire to reserve the 60 right to make such changes and alterations

as fall within the scope of the appended claims.

What I claim is:—

1. A music leaf turner including a pivot, a plurality of superposed leaf turning arms 65 loosely mounted on said pivot, means for effecting the movement of said arms singly in succession including a flexible thrust member and a spring pressed pin having a lug which is engageable with said arms, and a shoulder embodied by said pin whereby the same is limited in its downward movement.

2. A music leaf turner including a pivot, a plurality of superposed leaf turning arms 75 loosely mounted on said pivot, means for effecting the movement of said arms singly in succession including a flexible thrust member, a spring pressed pin capable of reciprocatory and arcuate movements, a lug on said 80 pin adapted to engage said arms, and a shoulder embodied by said pin for limiting downward movement thereof.

3. A music leaf turner comprising a pivot, a plurality of superposed leaf turning arms 85 loosely mounted on said pivot, means for effecting the movement of said arms singly in succession including, a spring pressed toothed element, a flexible actuating member operatively connected to said element, a toothed actuator mounted for movement on said pivot and adapted to co-act with said element, a spring pressed pin carried by said actuator, said pin being capable of reciprocatory, arcuate and turning movements, a 90 reduced extension on the lower end of said pin not greater in length than the thickness of either of said arms.

4. A music leaf turner comprising a casing, a pivot pin extending therethrough, a 100 plurality of superposed leaf turning arms, loosely mounted thereon for independent swinging movement, an actuator mounted on said pivot pin above the arms, means for revolving the actuator on said pivot pin, a 105 vertically arranged sleeve on the free extremity of said actuator, a trigger pin vertically movable in said sleeve, a head at the lower end of said pin, means for normally forcing the head against the arms, a lug on 110 said head adapted to engage behind the uppermost arm for revolving said uppermost arm with the actuator upon movement of the same, and means on the upper portion of said pin adapted to engage with the upper 115 face of the sleeve for retaining the head of said pin out of engagement with said arms.

In testimony whereof I affix my signature.

ANGELO DE STEFANO.
